CLAIM

The ornamental design for an operational illumination device, as shown and described.

DESCRIPTION

FIG. 1 is a front view of an operational illumination device; FIG. 2 is a back view of the operational illumination device; FIG. 3 is a side view of the operational illumination device; FIG. 4 is a side view of the operational illumination device; FIG. 5 is a top view of the operational illumination device; and,

FIG. 6 is a bottom view of the operational illumination device.

The broken lines shown in the drawings depict portions of the article and form no part of the claimed design.

1 Claim, 5 Drawing Sheets
